BASE FOR NATURAL OR ARTIFICIAL FLOWERS

Duncan Tong, 423 Central Bldg., 3 Pedder St.,
Hong Kong

Filed July 21, 1970, Ser. No. 24,050

Claims priority, application Great Britain Jan. 26, 1970

Term of patent 7 years

Int. Cl. D11—02

U.S. Cl. D35—3

FIG. 1 is a top perspective view from front and one side of a base for natural or artificial flowers showing my new design;

FIG. 2 is an elevation of other side;

FIG. 3 is an underneath plan;

FIG. 4 is a rear elevation; and

FIG. 5 is a section on line 5—5 of FIG. 4.

I claim:

The ornamental design for a base for natural or artificial flowers, as shown.
